UNITED STATES PATENT OFFICE.

CHARLES T. GRIFFITH, OF MOUNT AIRY, PENNSYLVANIA, ASSIGNOR TO PROCTOR & SCHWARTZ, INCORPORATED, OF PHILADELPHIA, PENNSYLVANIA, A CORPORATION OF PENNSYLVANIA.

STOCKING FORM.

Application filed May 15, 1922. Serial No. 561,197.

To all whom it may concern:

Be it known that I, CHARLES T. GRIFFITH, a citizen of the United States, residing in Mount Airy, Philadelphia, Pennsylvania, have invented certain Improvements in Stocking Forms, of which the following is a specification.

- My invention relates to certain improvements in stocking forms of the type known 10 as "fish tail" forms. In this type of form a stocking is creased at the sides and not at the front and back, and the heel of the stocking is drawn over a heel projection, as well as over a toe projection.
- 15 One object of the present invention is to make the toe portion of the stocking form of spring metal and to secure the toe portion to the rigid portion, which is the body of the form, and which is also the form for the 20 heel.

A further object of the invention is to provide means for adjusting the toe portion to accommodate stockings of different sizes.

In the accompanying drawings:

25 Fig. 1 is a side view of my improved stocking form;

Fig. 2 is an edge view;

Fig. 3 is an edge view, showing the toe portion of the foot of the form forced away from the heel portion;

Fig. 4 is an enlarged view, partly in section, showing the method of securing the spring metal toe portion of the foot section to the body of the form;

35 Fig. 5 is a perspective view, showing a stocking on the form; and

Fig. 6 is a view illustrating a modification of the invention.

Referring to the drawings, 1 is the body 40 of the form made of metal, which is comparatively rigid. This form is shaped to fit the leg portion of a stocking, as well as the heel portion, the end 2 being rounded, as shown, to fit the heel of a stocking. 3 is the 45 toe and foot portion of the form. This part is made of thin spring metal and is secured, in the present instance, to the body portion by screws 4, which extend into threaded holes 5 in the body portion. There 50 is a series of these holes, as shown clearly in Figs. 1 and 4, so that the foot portion can be adjusted to fit stockings of different sizes.

When a stocking is mounted on a form,

it is drawn onto the form until the toe portion *b* of the stocking *a*, Fig. 5, is in position. Then the toe portion of the form is forced away from the heel portion and the heel portion *c* is drawn down over the heel portion of the form by pressing down on the sides *d*. Then the spring foot portion is 60 allowed to return to its normal position. By this means, the entire stocking is pressed and shaped.

An alternative method of operation is to draw the stocking on the form until the toe 65 portion *b* of the stocking *a* is nearly in position. The form is then grasped near its upper end, with the operator's thumb and fingers on opposite sides thereof and the stocking is drawn downwardly until the toe 70 portion is in proper position on the form. During the downward movement of the stocking, the flexible foot portion 3 of the form is moved away from the body portion 75 as shown in Fig. 3. This permits the heel portion 2 of the form to enter the heel *c* of the stocking, the downward movement of the stocking and the position of the operator's thumb and fingers forcing the heel into proper position. The spring foot portion is 80 then allowed to assume its normal position, thus clamping and shaping the heel portion of the stocking.

In Fig. 6, a modification is illustrated in which the foot portion 3^a is preferably secured to the body portion 1^a by a rivet 4^a. The lower end of the foot portion is flanged at 6. This flange extends into a groove 7 in the body portion, rigidly holding the foot portion in position.

I claim:

1. A fish-tail stocking form made of metal and having a rigid heel portion and a flexible foot portion.
2. The combination in a stocking form, of 95 a body portion terminating in a heel portion; a foot portion secured to the body portion some distance from the end of the heel portion, said foot portion being made of 100 spring metal.
3. A stocking form of metal having a body portion terminating in a rigid heel portion; and a spring metal foot portion adjustably mounted on the body portion.

CHARLES T. GRIFFITH.
